(57) **CLAIM**

The ornamental design for octopost extrusion, as shown and described.

DESCRIPTION

The design is directed to an aluminum extrusion performing an octagon shaped structural element of unequal sides to provide structural strength substantially equivalent to a square-shaped member while providing an aesthetically pleasing appearance. The corners of the extrusion are formed with a slight radius and the extrusion can be utilized as a structural element of aluminum fabrications so as to be visible upon completion of the fabrication. As an example, such can be used in the construction of a canopy shelter. FIG. 1 is a top, left front perspective view of octopost extrusion showing my new design; FIG. 2 is a front elevational view thereof; FIG. 3 is a top plan view thereof; FIG. 4 is a bottom plan view thereof; and, FIG. 5 is a right side elevational view thereof, the left side view being a mirror image of the right side view shown. The broken line showing in the figures is for illustrative purposes only and forms no part of the claimed design.
